CLAIM

The ornamental design for an energy management system
controller, as shown and described.

DESCRIPTION

FIG. 1 is a front, right, top, perspective view of an energy
management system controller of a first embodiment show-
ing my new design;

FIG. 2 is a rear, left, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of the area "9" shown in FIG. 1;

FIG. 10 is an enlarged view of the area "10" shown in FIG.

2; and

FIG. 11 is an enlarged view of the area "11" shown in FIG.
2;

FIG. 12 is a front, right, top, perspective view of an energy
management system controller of a second embodiment
showing my new design;

FIG. 13 is a rear, left, bottom perspective view thereof;

FIG. 14 is a front elevation view thereof;

FIG. 15 is a rear elevation view thereof;

FIG. 16 is a left side elevation view thereof;

FIG. 17 is a right side elevation view thereof;

FIG. 18 is a top plan view thereof;

FIG. 19 is a bottom plan view thereof; and

FIG. 20 is an enlarged view of the area "20" shown in FIG.
12;

FIG. 21 is an enlarged view of the area "21" shown in FIG.
13; and,

FIG. 22 is an enlarged view of the area "22" shown in FIG.
13.

The broken lines in the figures are for environmental pur-
pose only and form no part of the claimed design.

The dot-dash broken lines encircling portions of the energy
management system controller in FIGS. 1, 2, 12 and 13 and
illustrated in enlarged view in FIGS. 9-11 and 20-22 form no
part of the claimed design.

1 Claim, 22 Drawing Sheets
